UNITED STATES PATENT OFFICE.

ROBERT HOPPNER, OF REPRESA, CALIFORNIA, ASSIGNOR OF ONE-HALF TO RUDOLPH MARSCHALL, OF STOCKTON, CALIFORNIA.

MONKEY WRENCH.

Application filed May 5, 1928. Serial No. 275,410.

This invention relates to improvements in monkey wrenches my principal object being to provide a wrench of this character in which the movable jaw is provided with means for enabling the same to be quickly moved toward the fixed jaw and to be then held against retractive movement in any position; and having conveniently operated means for releasing the holding means so that said movable jaw may be as quickly moved away from the fixed jaw when desired. This avoids the slow movement of the movable jaw as is common to the usual type of wrench.

15 A further object of the invention is to produce a simple and inexpensive device and yet one which will be exceedingly effective for the purpose for which it is designed.

These objects I accomplish by means of 20 such structure and relative arrangement of parts as will fully appear by a perusal of the following specification and claim.

In the drawings similar characters of reference indicate corresponding parts in the 25 several views:

Fig. 1 is a side elevation of my improved wrench.

Fig. 2 is a fragmentary sectional elevation thereof.

30 Fig. 3 is a fragmentary side elevation showing a modified jaw arrangement.

Fig. 4 is a similar view of another modified jaw arrangement.

Fig. 5 is a perspective view of the movable control pawl member of the movable jaw, shown detached from the wrench.

Referring now more particularly to the characters of reference on the drawings, and particularly at present to Figures 1, 2 and 40 5, the wrench comprises a straight shank 1 having at one end a handle 2 and in the other end a rigid jaw 3 projecting to one side of the shank. Slidable on and surrounding the shank is a sleeve 4 from which 45 a jaw 5 projects as an integral part to cooperate with the jaw 3. The side of the shank from which the jaws project is provided with a row of transversely extending ratchet teeth 6, facing toward the jaw 3.

50 Straddling the shank and disposed against the end face of the sleeve 4 farthest from the jaw 5 is a yoke 7 whose opening 8 is longer than the width of the shank. At one end of this opening the yoke is formed 55 with a tapering or wedge shaped pawl 9 to

engage the ratchet teeth. Between the pawl and the adjacent end of the yoke the latter is provided with a slot 10 which receives the shank of a headed screw 11 secured in and depending from the sleeve 4. This screw 60 holds the adjacent end of the yoke in place against the sleeve while permitting the yoke to have limited sliding movement relative thereto and to the shank. At its opposite end the yoke is provided with a longitudinally 65 extending pin 12 which is slidably guided in a lug 13 depending from the adjacent side of the sleeve 4. Fixed on the outer end of this pin is a button 14 which projects outwardly from the adjacent side 70 of the sleeve; a compression sleeve 15 between the lug and the button acting to pull in the yoke and maintain the pawl yieldably engaged with the ratchet teeth.

By means of this arrangement it will be 75 seen that the sleeve may be pushed freely toward the jaw 3, the pawl automatically moving past the shank teeth until the jaw 5 has assumed a proper cooperating position relative to the jaw 3 to engage a nut or bolt 80 head 16 disposed therebetween. The jaw 5 cannot then slip in the opposite direction, owing to the engagement of the pawl with one of the teeth, and also due to the direction in which said teeth and pawl face. 85 When it is desired to release the pawl to allow the movable jaw to slide away from the fixed jaw, it is only necessary to depress the button 14 and hold it depressed so that the pawl will clear the teeth, while at the same time pulling the sleeve along the shank. Owing to the position of the button on the sleeve and relative to the handle, this 90 operation may be readily done by a finger of the same hand grasping the handle, as will 95 be apparent.

Also owing to the direction of movement of the pawl necessary to clear the teeth, that is in a direction plane transversely of the shank, the pawl may be made to exactly 100 fit the teeth from top to bottom as shown in Fig. 2, so that a strong engagement between the pawl and the teeth is had. Also the yoke being disposed immediately against the sleeve, the pressure tending to slide the 105 sleeve along the shank and away from the jaw 3 when a nut is being engaged and turned, is not taken by the pin 12 or the screw 11, but is imparted to the entire area of the yoke surface. There is, therefore, no 110

tendency for the yoke to be stripped off or for the holding means to become weakened or distorted with severe pressure.

In the form of wrench shown in Fig. 3 the operating and control mechanism is the same, but the fixed jaw 3^a is T head or double and projects equal distance on both sides of the shank. Similarly the sleeve 4^a has a pair of opposed jaws 5^a to cooperate with the fixed jaws. The working face of one jaw 5^a is disposed out of parallel to the corresponding jaw 3^a as shown at 17, so as to permit of wedging engagement with a member disposed between the jaws if desired, while at the same time providing the wrench with a pair of parallel faced jaws for ordinary nut engaging purposes.

In the form of wrench shown in Fig. 4 there is also a pair of fixed jaws 3^b and a corresponding pair of movable jaws 5^b. The working faces of one cooperating pair of jaws while being parallel to each other are disposed at an angle to the faces of the other pair of jaws, so that the tool may be used as an offset wrench when conditions demand. Also the distance between one pair of jaws, is different than the distance between the other pair with the same setting of the sleeve 4^b, so that with such setting members of different sizes may be engaged by the wrench, such as the nut 18 of a bolt between one pair of jaws, and the relatively smaller head 19 of the same bolt by the other pair.

The need of constantly adjusting the sleeve to take care of every variation in nut or head sizes is therefore lessened consider-

ably over what is necessary with the ordinary wrench.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A wrench comprising a shank, a fixed jaw thereon, a sleeve slidable on the shank, a jaw on the sleeve to cooperate with the fixed jaw, ratchet teeth along the shank, a yoke surrounding the shank and transversely slidable relative thereto, a pawl formed with the yoke for engagement with the teeth, means for supporting and guiding the pawl end of the yoke from the adjacent face of the sleeve, a pin projecting longitudinally from the opposite end of the yoke, a lug depending from the sleeve and in which the pin is slidable, a button on the outer end of the pin projecting outwardly from the lug, the adjacent ends of the button and lug being hollowed out about the pin, and a compression spring about the pin in said hollowed out area.

In testimony whereof I affix my signature.

ROBERT HOPPNER.
